(57) **CLAIM**

The ornamental design for a beam clamp, as shown and described.

DESCRIPTION

FIG. 1 is a perspective view of a beam clamp design showing my new design.

FIG. 2 is a front view of a beam clamp.

FIG. 3 is a rear view of a beam clamp.

FIG. 4 is a left side view of a beam clamp.

FIG. 5 is a right side view of a beam clamp.

FIG. 6 is a top view of a beam clamp.

FIG. 7 is a bottom view of a beam clamp.

FIG. 8 is an exploded view of a beam clamp; and,
FIG. 9 is an enlarged view of the beam clamp taken from the circle part in FIG. 1.

Any shading is not features of the design but are utilized to illustrate the surface contours of the beam clamp design in the drawings.

The dot-dot-dash lines in FIGS. 1 and 9 depict the boundaries of the enlargement that form no part of the claimed design.
